UNITED STATES PATENT OFFICE

141,173

DESIGN FOR A PINCUSHION

William B. Hork and Edith P. Seaberg, Chicago,
Ill.; said Seaberg assignor to said Hork

Application March 29, 1945, Serial No. 118,754

Term of patent 7 years

(Cl. D3—19)

To all whom it may concern:

Be it known that we, William B. Hork and Edith P. Seaberg, both citizens of the United States, residing at Chicago, in the county of Cook and State of Illinois, have invented a new, original, and ornamental Design for a Pincushion, of which the following is a specification, reference being had to the accompanying drawing, forming part thereof.

The figure on the drawing is a front perspective view of a pin cushion showing our new design. The edging shown on the front and side continues around the pincushion.

We claim:

The ornamental design for a pincushion, as shown and described.

WM. B. HORK.
